Attorneys.

UNITED STATES PATENT OFFICE.

HOWARD MARION WILLIAMS, OF BOULDER, COLORADO.

LOOSE-LEAF SHEET.

1,405,882.

Specification of Letters Patent.

Patented Feb. 7, 1922.

Application filed June 24, 1920. Serial No. 391,391.

To all whom it may concern:

Be it known that I, HOWARD M. WILLIAMS, a citizen of the United States, residing at Boulder, in the county of Boulder and State 5 of Colorado, have invented certain new and useful Improvements in Loose-Leaf Sheets; and I do hereby declare the following to be a full, clear, and exact description of the invention, such as will enable others, skilled 10 in the art to which it appertains to make and use the same.

This invention relates to loose leaves for ledger account systems such as are now in common use in banks and similar institutions where it is desirable to furnish periodical statements of accounts to customers.

The object of the invention is to provide a simple, efficient and economical form of sheet for systems of this character by means 20 of which a substantial economy of paper is secured and a considerable amount of labor is saved.

The invention consists in the construction, arrangement and combination of parts as 25 hereinafter more fully described and claimed.

One sheet of drawings accompanies this specification as part thereof, in which like reference characters denote like parts 30 throughout.

Figure 1 represents a filing drawer containing loose leaves involving the present invention,

Figure 2 shows the leaf opened out,

Figure 3 shows the leaf folded down.

Referring to the drawings, *a* represents a normal sized leaf adapted to contain the account of an average customer or depositor, *b* represents an integral part of the sheet 40 from which part *a* is formed, but is only of approximately half the size of part *a*. Part *b* is folded down on the line *e* to overlay part *a*, as shown in Figure 3.

The bottom of part *a* is provided with 45 suitable slots *d* adapted to receive rods or similar parts of a binder or filing drawer such as *f*.

Both parts *a* and *b* are suitably printed and ruled as shown at *a*, the ruling and

printing on both parts being identical and 50 reading from the folded edge downward.

In practice with loose leaf account systems, a substantial number of all accounts are small, but the sheets adopted by any institution must be sufficiently large to accommodate the average customer's account. With ordinary sheets, the small accounts 55 occupy only a small part of the sheet, but an entire sheet must be devoted to it and removed periodically regardless of the 60 amount actually used, for delivery to the customer.

With the present invention, the regular sheets are interspersed with sheets involving the present invention and the accounts of 65 customers uniformly having small accounts is placed on sheet *b*. By reason of its arrangement in conjunction with part *a*, small sheet *b* is retained at the top of the file subject to ready inspection and thus avoiding 70 the possibility of being overlooked, such as would be inherent with the use of ordinary half sized sheets.

When at the end of the month or similar period for rendering accounts, small sheet 75 *b* is torn from part *a* and delivered, part *a* remains in the binder ready to be used for an average sized account.

It will be obvious that this invention will save a substantial amount of paper, will 80 prevent mistakes by keeping the headings of all accounts at the same level in the filing case, and will avoid the necessity of replacing a substantial number of sheets.

What I claim is:

1. A loose leaf for accounts, comprising a sheet and a second smaller sheet integral therewith, formed by a transverse fold parallel with one edge and adapted to be folded back on the larger sheet, the upper 90 faces of both the larger sheet and the back folded smaller sheet being similarly inscribed and ruled to read from the folded edge downward for indexing purposes.

2. A loose leaf for accounts, comprising a sheet having means on one edge for securing the sheet in a holder, said sheet being 95 folded parallel with said edge so that a part

of the sheet is folded back and the upper faces of the sheet and back folded part thereof similarly inscribed and ruled to read from the fold downward toward the holding edge for indexing purposes.

3. The combination of a plurality of normal sized sheets and a plurality of sheets having one edge adapted to be held by a holder and folded parallel with said edge

to form normal sized sheets having smaller 10 sheets back folded from said fold, the faces of said normal sized sheets, and both parts of said back folded sheets being similarly inscribed and ruled to read from the folded and upper edge downward for indexing 15 purposes.

In testimony whereof I affix my signature.
HOWARD MARION WILLIAMS.
